US00D448672B1

(12) **United States Design Patent** (10) Patent No.: **US D448,672 S**
Cheng et al. (45) Date of Patent: ** Oct. 2, 2001

(54) **CONTAINER**

- (75) Inventors: **Jizu John Cheng**, Burr Ridge; **Philip G. Kraft**, Chicago Heights; **Richard G. Kraft**, Joliet; **Jeffrey D. Krich**, Roselle; **Sherry Yuan**, Oak Lawn; **Robert J. Crawford**, Lisle, all of IL (US)
- (73) Assignee: **Crown Cork & Seal Technologies Corporation**, Alsip, IL (US)
- (**) Term: **14 Years**

(21) Appl. No.: **29/118,640**(22) Filed: **Feb. 11, 2000**(51) LOC (7) Cl. .... **09-01**(52) U.S. Cl. **D9/530**

(58) Field of Search D9/300, 434, 520, D9/530, 537-539, 541-542, 545, 549, 551-552, 554-559, 564-565, 567-570, 574; 215/381-384; 220/671-672; 222/210, 212-213, 215

(57) **CLAIM**

The ornamental design for a container, as shown and described.

DESCRIPTION

FIG. 1 is a perspective view of this invention for a container; FIG. 2 is a side elevation view of the container of FIG. 1, the opposite side being a mirror image; FIG. 3 is a rear elevation view of the container of FIG. 1; and, FIG. 4 is a front elevation view of the container of FIG. 1. Any broken lines in the drawings are in the views for illustrative purposes only and form no part of the claimed design.
